UNITED STATES PATENT OFFICE.

JAMES A. G. GRANT, OF IOLA, KANSAS.

DIRECTION-INDICATOR.

1,369,423.

Specification of Letters Patent. Patented Feb. 22, 1921.

Application filed November 22, 1919. Serial No. 339,919.

To all whom it may concern:

Be it known that I, JAMES A. G. GRANT, a citizen of the United States, residing at Iola, in the county of Allen and State of

5 Kansas, have invented certain new and useful Improvements in Direction-Indicators, of which the following is a specification, reference being had to the accompanying drawings.

10 This invention relates to certain improvements in direction indicators, and has relation more particularly to a device of this general character especially designed and adapted for use in connection with automobiles and the like, and it is an object of 15 the invention to provide a novel and improved indicator of this type which can be manually operated with convenience and facility, and preferably through the instrumentality of a foot pedal.

It is also an object of the invention to provide a device of this general character including a pair of signaling members or semaphores supported at opposite sides of 25 a vehicle body, together with means whereby each of said signaling members or semaphores may be elevated or moved into a position to indicate that a turn is about to be made in the direction of travel of the vehicle 30 and wherein means is provided for maintaining each of said signaling members or semaphores in an inoperative position.

Another object of the invention is to provide a novel and improved device of this 35 general character wherein is embodied a signaling member or semaphore in simulation of a human arm or hand, so that when the signaling member or semaphore has been moved into a position extending outwardly 40 from the vehicle, an appearance will be presented in close imitation of the extended arm and hand of an occupant of a car, so that the signal will cause no confusion in connection with the now prevalent practice 45 of indicating a turn by the outward extending of a hand and arm, by an occupant of the car.

An additional object of the invention is to 50 provide a novel and improved device of this general character wherein the signaling member or semaphore is provided with light emitting means, whereby the signal may be clearly observed after nightfall, and wherein in said light emitting means is electrically

operated and under control of the mechanism for moving or adjusting the signaling member or semaphore S into signaling position.

The invention consists in the details of construction and in the combination and arrangements of the several parts of my improved direction indicator, whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 70 better understood, I will now proceed to describe the same with reference to the accompanying drawings, wherein:

Figure 1 is a fragmentary view in side elevation, with portions broken away, of the 75 device, having applied thereto a direction indicator constructed in accordance with an embodiment of my invention;

Fig. 2 is a view in rear elevation of the structure as disclosed in Fig. 1, one of the 80 signal members or semaphores being raised and the other lowered;

Fig. 3 is an enlarged fragmentary view partly in vertical section and partly in elevation illustrating the mounting of one of 85 the signaling means or semaphores, as herein included, together with a portion of the operating mechanism, said member or semaphore being lowered;

Fig. 4 is a fragmentary view partly in 90 section and partly in elevation of the member or semaphore raised or elevated;

Fig. 5 is a sectional view taken substantially on the line 5—5 of Fig. 4;

Fig. 6 is a view in end elevation of the 95 globe as herein embodied;

Fig. 7 is a fragmentary view partly in section and partly in elevation of an operating pedal comprised in the operating mechanism, together with the parts concomitant thereto;

Fig. 8 is a fragmentary view partly in section and partly in front elevation of the structure as illustrated in Fig. 7.

Fig. 9 is a fragmentary view in bottom 105 plan of the operating mechanism, as herein embodied, the operating circuits for the lamps being diagrammatically illustrated;

Fig. 10 is a fragmentary sectional view illustrating a modified form of invention, and,

Fig. 11 is a fragmentary sectional view 5 illustrating a still further modified form of invention.

As disclosed in the accompanying drawings, B denotes a vehicle body of a conventional type employed in connection with 10 motor-driven vehicles, and wherein the side walls 1 are of the conventional double construction provided with an intervening space α .

Secured to the outer face of each of the 15 side walls 1 substantially midway the length thereof and in close proximity to its upper margin is a member M. The member M includes the base flanges 2, through which bolts or other suitable members are adapted 20 to be disposed for securing the member M in applied position. The member M is also provided with the outwardly facing socket 3, provided in its base with an opening 4, in register with an opening 5, formed in the 25 outer section of the wall 1.

The socket 3 is intersected by a removable bolt or pin 6, disposed substantially horizontally or in a direction longitudinally of the body B. The bolt or pin 6 serves as a 30 pivot for the vertically swinging signaling member or semaphore S.

The signaling member or semaphore S comprises an elongated arm 7, having one end portion 7^a arcuate, and extending within 35 the socket 3 for pivotal engagement with the bolt or pin 6. The portion 7^a is continued by a restricted extension or tail 8, which is directed through the registering openings 4 and 5, and extends within the 40 intervening space α of the wall 1.

The free end portion of the extension or tail 8 is provided with the opening 9 to afford means whereby the eye or hook 10, provided at an end of an elongated rod 11 45 may be interlocked and hingedly or pivotally engaged with said extension or tail 8.

The rod 11 is vertically disposed and housed within the wall 1, and the lower end portion of the rod 11 is operatively 50 engaged through the instrumentality of a link 12 with a substantially horizontally disposed arm 14 of a bell crank lever C.

The second arm 15 of the lever C is downwardly directed, and the heel portion 16 55 of the lever C is provided with an opening 17 to receive the outstanding stud 18 carried by the bracket 19. The bracket 19 is substantially T shape in form, and is provided with the openings 20^a, through which 60 screws or the like are directed for properly anchoring the bracket 19 in applied position upon the under face of the bottom or floor 20 of the body B.

The depending arm 15 of the bell crank 65 lever C is provided with an opening 21 to

permit the requisite operative engagement therewith of an end portion of a substantially horizontally disposed rod 22, extending rearwardly of the body B. The rear end portion of the rod 22 is operatively engaged 70 with an arm 23 of a bell crank lever C', said engagement being facilitated by an opening 24 in the outer end portion of said arm 23.

The outer extremity of the second arm 75 25 of the bell crank lever C' is provided with an opening 26 to permit operative engagement therewith of an end portion of a rod 27, extending inwardly and transversely of the body B. The opposite end 80 portion of the rod 27 is operatively engaged with the outer extremity of an arm 28 of a bell crank lever C², said arm 28 being substantially in parallelism with the arm 25, and is also provided in its free extremity 85 with an opening 29 for the desired engagement therewith of a rod 27. The bell crank levers C' and C² each have their heel portion provided with an opening 31, through which extends a stud 32 depending from a plate 90 33 secured to the under surface of the bottom or floor 20. By this it will be at once understood that the bell crank levers C' and C² have horizontal and substantially coplanar swinging movement. Each of the levers C' and C² is held in applied position upon its coacting stud 32 by a pin 34, directed through the stud at a point below the heel portion of the bell crank lever.

The second arm 35 of the bell crank lever 100 C² is provided with an opening 36 to permit operative engagement with said arm of an end portion of a forwardly directed rod 37.

38 denotes a bracket depending from the floor or bottom 20 of the body B, having its 105 lower end terminating in a substantially horizontally and transversely directed bearing 39, through which is disposed a shaft 40. The shaft 40 extends beyond the opposite ends of the bearing 39, and each extended end portion is disposed through an opening 41 provided in the heel portion of a bell crank lever L. One arm 42^a of the lever L normally extends rearwardly and upwardly, and is provided in its outer or 110 free end portion with an opening 42 to afford means whereby the forward end portion of the rod 37 may be operatively engaged therewith. The second arm 43 is upwardly directed, and its free end portion 115 is provided with a longitudinally disposed slot 44. Straddling the upper or free end portion of the arm 43 is a fork 45 carried by the lower end portion of the section 46 comprised in the pedal P. The fork 45 is 120 bridged by a stud or pin 47, which extends through the slot 44, so that upon endwise movement of the pedal P the bell crank lever L will be operated to cause the signaling member or semaphore S to assume an ex- 130

tended or substantially horizontal position to give indication that the vehicle is about to make a turn in the direction in which said signaling member or semaphore S is extended.

Connected to the upper portion of the bracket 38 or other support is an end portion of a retractile member 47, and the opposite end portion of said member is secured 10 to the upstanding arm 43 of the bell crank lever L. As herein embodied, the retractile member 47 constitutes a coil spring, and said member operates to maintain the arm 43 in its normal position, and, when the operating mechanism is released, to facilitate the return of the signaling member or semaphore S to its inoperative position.

The pedal P extends upwardly and rearwardly through the bottom or floor 20 on an angle of substantially 45°, and through a bushing 49 extending through said bottom or floor 20.

The pedal P comprises the lower section 46 and an upper section 50, detachably connected as at 51. The connection 51 preferably comprises a threaded shank b carried by the lower section 46, and engaging within a socket c formed in the lower end of the section 50. The forming of the pedal P in two sections is necessary in order to properly mount the pedal P, in view of the fork 45 carried by the lower end of the section 46 and the tread 51, carried by the upper end of the section 50.

The portion of the pedal P within the bushing 49 is such as to permit the pedal P to have slight rocking movement in a direction longitudinally of the body B; and the rear edge of the upper section 50 of the pedal P is provided with a notch 52 to receive a lug 53 carried by the bushing 49, whereby the pedal P is normally locked against downward movement, and the signaling member or semaphore S retained in inoperative position. The forward portion of the bushing 49 is provided with a socket or recess 54, in which is mounted an expansible member 55, which operates to constantly urge the pedal P rearwardly to assure the requisite coaction of the lug 53 with the pedal P, as afforded by the notch 52. When it is desired to swing a signaling member or semaphore S upwardly into working position, the operator engages a foot with the tread 51, and swings the pedal P against the action of the expansible member 55 and thereby disengages the pedal P from the lug 53. The pedal P can then be depressed to accomplish the desired upward swinging movement of the signaling member or semaphore S. When the pedal P is released from pressure, as by the removal of the foot therefrom, the signaling member or semaphore S automatically drops to its lowered or inoperative position and the pedal P moves upwardly and

the desired interlock of the lug 53 with the pedal P is accomplished automatically.

The signaling member or semaphore S returns to its lowered or inoperative position by gravity. In order to facilitate the upward swinging movement of said member or semaphore S I find it of advantage to secure to the extension or tail 8 an end portion of a retractile member 56, herein disclosed as a coil spring, and the opposite end portion of said member is suitably secured to the bottom or floor 20, or at a suitable point below the extension or tail 8. The member 56 is of a tension insufficient to raise the signaling member or semaphore S, but of a strength to materially minimize the manual operation.

In practice it is preferred that the tread 51 be provided at its forward portion with an upstanding flange 57, so that the pedal P may be conveniently operated by the heel of a foot, so that the toe portion can be conveniently used in connection with a portion of the mechanism comprised in the vehicle or automobile proper.

Extending outwardly from the wall 1 is a U shaped bracket 58, which receives the lower portion of the signaling member or semaphore S when in its lowered position, and serves as a support therefor, and particularly to maintain said member or semaphore S against accidental movement in a direction longitudinally of the body B, which would otherwise result in injuring the member.

As herein before described, the structure as particularly related to each of the signaling members or semaphores S is of a character adapted to be applied to a built body. In a new structure the outer section of a side wall may be provided with an outstanding portion 59, having formed therein a vertically disposed groove or channel 60, in the upper end portion of which the signaling member or semaphore S' is pivotally supported for vertical swinging movement. This groove or channel 60 is also of a depth to substantially entirely receive the signaling member or semaphore S' when in its dropped or lowered position. If preferred a new car may be constructed in each side wall with a vertically disposed groove or channel 61, extending inwardly of the back structure 62 of a seat, and particularly the front seat when the body is of a touring type.

The arm 7 of each of the signaling members or semaphores S is substantially U shape in cross section with its open longitudinal face disposed inwardly or downwardly, and the outer end of said arm is also open. The closed longitudinal face of the arm 7 is continued by a strap 63 returned upon itself to afford a retaining loop member of desired configuration and the

free end portion of the strap 63 is adapted to be inserted a slight distance within the open or outer end of the arm 7 and held thereto by a removable pin or bolt 64, said pin or bolt 64 holding the member 63 in a position to effectively maintain against displacement the globe G.

The globe G comprises an elongated tubular member formed preferably of glass, and 10 the side walls of said globe G are substantially concavo-convex with the convex surfaces outwardly directed. Pressed outwardly from each side face of the globe G is a simulation of an extended hand with 15 the wrist portion thereof arranged at an open end of the globe G. The wrist portion of the globe G extends partially within the outer or open end of the arm 7, and, as hereinbefore stated, is effectively maintained 20 in applied position by the strap 63 and the coacting pin or bolt 64.

65 denotes a block depending from the upper or closed longitudinal wall of the arm 7, and said block serves as a support for 25 the socket 66, extending in a direction longitudinally of the arm 7. The socket 66 is in electrical connection in a manner to be hereinafter more particularly described, with a source of electrical energy E, pref- 30 erably dry storage batteries arranged under the front seat structure of the car body.

Coacting in a conventional manner with the socket 66 is an incandescent lamp 67, which extends within the globe G so that 35 when the lamp is burning the rays of light emitted therefrom will effectively illuminate the globe and more particularly the simulation of a hand. Although not necessary, it is preferred that the portions of the globe G 40 surrounding the simulation of the hand be opaque or rendered impervious to light.

It will be readily seen that the manner of mounting the globe G, as just set forth, is such as can be readily replaced or re- 45 moved in accordance with the requirements of practice, and particularly in the event of said globe becoming broken or otherwise unfit for use. This ready removal or replacement of the globe G also facilitates the 50 desired application or replacement of the lamp 67. Telescoping within the arm 7 from below is an elongated member 68 substantially U shape in cross section, and V shape in side elevation. The apex portion 55 of the member 68 is pivotally engaged, as at 69, within the arm 7 at a point in close proximity to the arcuate portion 7^a of said arm. Each of the side walls 69^a of the member 69 60 adjacent the broad end thereof is provided 60 with a transversely disposed arcuate slot 70. Directed through the slots 70 of the side walls 69^a is a cross member or pin 71, carried by the side walls of the arm 7 adjacent the lower edges thereof. By this means the 65 member 69 is capable of limited swinging

movement with respect to the arm 7, so that when the said arm 7 is raised, the member 69 will drop outwardly therefrom to apparently increase the width of the arm 7, so that the same may be more readily discerned. 70 When the arm is dropped and reaches its lowered position, the member 69 readily moves inwardly of the arm 7.

One of the conductors α coacting with the socket 66 leads directly to the electrical 75 source E. The second connection for the socket 66 includes a conductor γ in electrical connection with the rod 11. The operating circuit is continued through the rod 11, the bell crank lever C, the rod 22, the bell crank lever C', the rod 27 and the bell crank lever C². The arm 28 of the bell crank lever C², when said lever has been moved to effect the desired raising of a signaling member or 80 semaphore S, engages a spring contact member 72 carried by the bottom or floor 20 of the body B, and in electrical connection through the conductor α with the electrical 85 source E. By this it will be readily seen that the circuit for the lamp 67 of each 90 of the signaling members or semaphores S will not be closed until after the signaling member or semaphore S has begun to swing outwardly. Interposed upon the conductor α is a circuit breaker 73, whereby the circuit for the lamps 67 may be broken during 95 the day or during those periods when it is not desired that the lamps 67 burn when the signaling members or semaphores S are extended.

It is to be understood that the necessary parts of the operating mechanism for each of the signaling members or semaphores S are suitably insulated, so that the operating circuit for each of the lamps 67 will be properly maintained. 100

From the foregoing description it is thought to be obvious that a direction indicator constructed in accordance with my invention is particularly well adapted for use 110 by reason of the convenience and facility with which it may be assembled and operated, and it will also be obvious that my invention is susceptible of some change and modification without departing from the 115 principles and spirit thereof, and for this reason I do not wish to be understood as limiting myself to the precise arrangement and formation of the several parts herein shown in carrying out my invention in practice except as hereinafter claimed. 120

I claim:

1. A direction indicator for vehicles including a semaphore supported for vertical swinging movement, mechanism for moving 125 said semaphore upwardly, said semaphore moving by gravity in the opposite direction, the pivoted end portion of the semaphore being provided with a tail, and a spring engaged with said tail for constantly 130

imposing a pull upon the semaphore to facilitate its upward movement said spring being insufficient in itself to impart movement to the semaphore.

5 2. The combination with an automobile embodying the usual body and provided with a pair of signal arms adapted to be swung to operative and inoperative positions, of operating mechanism for said signal arms embodying, a bracket secured to and extending downwardly from the bottom of the body of the automobile, a transverse shaft carried by the lower end of said bracket and having its ends projecting upon 10 each side thereof, a bell crank lever mounted upon each of the ends of said shaft, each of said levers being provided in one arm thereof with a slot, retractile members each having one end connected to the slotted arm of 15 one of said bell crank levers and the opposite end connected to the under portion of the body of the automobile, bushings extending through the bottom of the frame of the automobile and each provided with a

bore, a lug formed upon each of said bushings and projecting outwardly from the rear face of the bore thereof, pedals longitudinally shiftable through said bushings and provided upon their lower ends with bifurcated members, pins extending through the arms of said bifurcated members and the slots of the arms of said bell crank levers, the bore of said bushings being of sufficient size to permit transverse movement of said pedals therein, said pedal being provided with a notch adapted to engage the lug of said bushing and to limit the downward movement of the pedal, retractile members mounted within said bushings and engaging the front faces of said pedals to 40 force said notches into engagement with said lugs, and means operatively connecting the free arms of said bell crank levers with said signals.

In testimony whereof I hereunto affix my 45 signature.

JAMES A. G. GRANT.
